UNITED STATES PATENT OFFICE.

HILARY F. WHALTON, OF KEY WEST, FLORIDA.

STARTING MECHANISM.

1,010,835.

Specification of Letters Patent.

Patented Dec. 5, 1911.

Application filed March 25, 1911. Serial No. 616,920.

To all whom it may concern:

Be it known that I, HILARY F. WHALTON, a citizen of the United States, residing at Key West, in the county of Monroe and State of Florida, have invented certain new and useful Improvements in Starting Mechanism; and I do hereby declare the following to be a full, clear, and exact description of the invention, such as will enable others skilled in the art to which it appertains to make and use the same.

This invention relates to starting mechanism for motors, such as gas engines used on automobiles and aeroplanes; and it consists in the novel construction and combination of the parts hereinafter fully described and claimed.

In the drawings, Figure 1 is a side view of the starting mechanism as constructed according to this invention. Fig. 2 is a plan view of the starting mechanism.

A is the main driving shaft of a motor of any approved construction, such as a gas engine.

B is a ratchet toothed wheel formed in two halves or sections which are clamped upon one end portion of the shaft A by means of bolts b. This wheel is made in sections and is provided with clamping bolts so that it can be applied to any existing engine without being bored to accurately fit its shaft and so that a key-way does not have to be cut in the shaft.

C is the starting lever provided at one end with a bearing c made in two sections and provided with bolts c' for securing them together. The bearing c is journaled loose on the shaft A adjacent to the wheel B.

D is a pawl which is pivoted to the lever C by a pin d, and e is a spring of moderate strength for causing the pawl to engage with the teeth of the ratchet wheel when required. The pawl D has an arm or extension d' on the other side of its pivot from its point.

E is a curved trip which is secured to a bracket F by means of bolts f. The bracket F is secured to a support G which may be a portion of the frame of the engine or any framework or stationary object secured adjacent to it. The trip is formed separate from the bracket and the bolts are arranged

so as to permit its position to be adjusted. The trip has a plate e which is provided with a longitudinal slot g so that the plate 55 can be slid longitudinally on the bracket F to adjust the trip, when the nuts of the bolts f are slack. In this manner the bracket can be secured to any existing support, and the trip can be secured after being adjusted 60 to project at any desired distance from the support.

H is a retracting spring which is considerably longer and stronger than the spring e. One end of the spring H is secured to a stationary object such as lug h 65 on the bracket F, and its other end is connected to the operating lever C.

The trip is arranged in the rearward path of the arm d', and the strong spring H retracts the starting lever, and also moves the pawl out of engagement with the teeth of the ratchet wheel by overcoming the force of the lighter spring e.

I is a flexible connection attached to the 75 free end portion of the starting lever, and carried by a guide sheave or sheaves i to any desired point.

When the engine is to be started, the lever C is moved sharply a few times in the 80 direction of the arrow in Fig. 1. The pawl is disengaged automatically by the trip and strong spring as soon as the engine commences to work. The engine shaft can be provided with a starting crank in the ordinary way, if desired, in addition to the starting devices hereinbefore described. The trip E is arranged under the spring H, and it is adjusted longitudinally of the said spring so that the extent of its projection 85 from the said frame can be provided for and also so that the spring will operate to release the pawl without jamming it against the trip. The spring retracts the pawl automatically, and enables the lever C to be 90 operated from a distance by means of the flexible connection I which is pulled in the opposite direction from the spring and then released to permit the spring to act.

What I claim is:

The combination, with an engine shaft, of a toothed wheel secured on the shaft, a starting lever mounted on the shaft, a pawl pivoted to the lever and engaging with the

said wheel, a stationary trip, a spring which moves the lever in one direction and presses it against the said trip thereby disengaging it from the said wheel, a support, a bracket secured to the said support, means for connecting the said trip to the said bracket and permitting the trip to be adjusted longitudinally of the said spring, and a flexible

connection attached to the said lever and enabling it to be operated from a distance. 10

In testimony whereof I have affixed my signature in the presence of two witnesses.

HILARY F. WHALTON.
